STUDY CARREL

Albert A. Canfield, Royal Oak, Mich., assignor to Oakland Community College, Bloomfield Hills, Mich., a corporation of Michigan

Filed Mar. 14, 1968, Ser. No. 10,983

Term of patent 14 years

Int. Cl. D6—01

U.S. Cl. D33—11

FIGURE 1 is a front elevational view of a study carrel showing my new design;

FIGURE 2 is a right-hand side elevational view thereof;

FIGURE 3 is a left-hand side elevational view thereof;

FIGURE 4 is a top plan view thereof;

FIGURE 5 is a sectional view taken along the lines 5—5 of FIGURE 1; and

FIGURE 6 is an isometric view thereof.

The dominant features of my design reside in those portions shown in full lines on the drawing.

I claim:

The ornamental design for a study carrel, substantially as shown and described.
